UNITED STATES PATENT OFFICE.

RALPH B. WEBER, OF ST. CHARLES, MISSOURI, ASSIGNOR TO L. A. SCHOENBERG, OF ST. CHARLES, MISSOURI.

LIFTING-JACK.

1,268,410.

Specification of Letters Patent.

Patented June 4, 1918.

Application filed July 27, 1917. Serial No. 183,083.

To all whom it may concern:

Be it known that I, RALPH B. WEBER, a citizen of the United States, residing at the city of St. Charles, county of St. Charles, 5 and State of Missouri, have invented a new and useful Lifting-Jack, of which the following is a specification.

This invention relates to lifting jacks, and is primarily adapted for use for raising 10 automobiles and other vehicles, but may be applied to any use to which such an implement is applicable.

The object of the invention is to provide a lifting jack comprising a base and a 15 pedestal pivoted to the base and movable to any required position in respect of the base to enable the pedestal to maintain a vertical adjustment, while the base is at any required angle, whether at right angles or oblique 20 angles relative to the pedestal, in combination with lifting mechanism in connection with the pedestal comprising a shank or stem adapted to engage with the part to be lifted and manipulative mechanism for actuating the shank or stem and holding it in 25 its different adjustments.

In the accompanying drawing, in which I have illustrated one embodiment of the invention,

30 Figure 1 is a side elevation of the lifting jack with the base upon a horizontal support, and the pedestal extended vertically.

Fig. 2 is a side elevation of the device with the base upon an inclined or oblique 35 support and the pedestal extending vertically.

Fig. 3 is a cross sectional view of the base on the line 3—3 of Fig. 5, illustrating the pivotal connection of the pedestal therewith.

40 Fig. 4 is a longitudinal sectional view of the base on the line 4—4 of Fig. 5, illustrating the pivoted arm on the pedestal located in the base.

Fig. 5 is a plan view of the base, the 45 pedestal being in section on the line 5—5 of Fig. 4.

Fig. 6 is a sectional view of the base on the line 6—6 of Fig. 4, illustrating the removable part or section of the base coöperating 50 with the remaining portion thereof to hold the pedestal in pivotal connection with the base.

The jack includes a base comprising a supporting part 1 adapted to bear upon the

ground and to support the pedestal and a 55 coöperating removable part 2.

The supporting part 1 is provided with a flat under surface and with a horizontal cylindrical recess or bearing 3. A transverse slot 4 through the top of the part 1 intersects and opens into the bearing 3 and affords space for the movement of the pedestal as will hereinafter appear. The removable part 2 is held in connection with the part 1 by a releasable binding element 5 which in 60 the form shown is a screw passing through the lower portion of the supporting part 1 and into the removable part 2, so that the said part 2 will be firmly held in position thereby.

The part 2 thus arranged constitutes the upper portion of one end of the base and is symmetrical with the opposite end of the part 1 and has its upper side in the same plane with the upper side of said part 1. 70 The inner end of the part 2 abuts against the part 1 and forms one of the side walls of the slot 4. The part 2 is formed with a cylindrical recess 6 in axial alinement with the recess 3 and adapted to serve as a bearing 75 for the transverse axis of the pedestal.

The pedestal 7 is a strong metallic part and is provided with an axis member 8 which is in the form of two axially alined cylindrical arms which are at right angles 80 to the axis of the pedestal 7 and which have bearing within the recesses 3 and 6, the pedestal extending through the slot 4 and being capable of lateral oscillation as illustrated in Fig. 3. By this arrangement 85 the base can be placed in any necessary position, whether upon a horizontal or an inclined support, and the pedestal can be maintained in a vertical position irrespective of the support upon which the base is 90 mounted.

The lifting mechanism which is combined with the pedestal is conventionally illustrated and, as shown, comprises the usual toothed member 9 operating within a frame 100 10 on the pedestal and controlled by the lever and ratchet devices 11 of the usual or any preferred type. These ratchet devices and their coöperation with the member 9 are of a well known type and 105 specifically are no part of the present invention, it being understood that my lifting jack is capable of being combined with this

form of lifting mechanism or any of the other standard or preferred forms.

A lifting jack of this construction is of special use as a lifting jack for automobiles and may conveniently be employed for lifting the automobile, whether the vehicle is standing upon a level or an inclined surface. In either case the pedestal and lifting mechanism will be vertical, while the base will stand directly against and upon the surface of the ground, whether the surface is level or inclined. Lateral or torsional strain upon the pedestal is thus prevented so that the parts may be made of smaller dimension and weight than would be required if it were necessary for them to withstand the lateral strains incurred by devices of this character in which the base is rigid with the pedestal when the device is used upon inclined surfaces; in the devices of rigid construction when used in the conditions mentioned only one edge of the face engages the ground so that the entire weight of the vehicle exerts a lateral strain upon the pedestal at its connection with the base. This strain is entirely eliminated by my device.

What I claim and desire to secure by Letters Patent of the United States, is:—

1. A lifting jack, comprising a base composed of a supporting part having a transverse slot provided with oppositely inclined end walls, said part having a recess whose bottom wall is in alignment with the bottom wall of said slot, a removable part mounted on the supporting part and having a recess in axial alignment with and of the same

diameter as the recess in the supporting part, and an element removably binding the removable part upon the supporting part; a pedestal extending into said slot and being movable in opposite directions into contact with the inclined end walls of said slot, respectively; two axially aligned cylindrical arms integral with and at right angles to said pedestal journaled in said recesses and arranged to rock therein as the pedestal is oscillated in said slot; and lifting mechanism in connection with said pedestal.

2. A lifting jack, comprising a base composed of a supporting part having a horizontal cylindrical recess therein, and having a transverse slot through the upper part thereof intersecting and opening into the recess, a removable part seated upon the supporting part and having a cylindrical recess in axial alignment with the recess in the supporting part at the opposite side of said slot, and a binding element holding the removable part on the supporting part; a pedestal extending into the slot; two axially aligned cylindrical arms on the lower end of the pedestal journaled in said cylindrical recesses respectively; and lifting mechanism in connection with the pedestal.

In witness whereof, I have signed this specification in the presence of two subscribing witnesses.

RALPH B. WEBER.
